Patented Nov. 23, 1915.

UNITED STATES PATENT OFFICE.

HOMER EMERSON HASKELL, OF HUNTINGTON, WEST VIRGINIA.

INJECTOR.

1,161,127.

Specification of Letters Patent. Patented Nov. 23, 1915.

Application filed June 26, 1913. Serial No. 775,874.

To all whom it may concern:

Be it known that I, HOMER E. HASKELL, a citizen of the United States, and a resident of Huntington, in the county of Cabell and State of West Virginia, have invented a new and Improved Injector, of which the following is a full, clear, and exact description.

Among the principal objects which the present invention has in view are: to provide an injector with automatic closure members to work quickly and smoothly; to provide an injector of the character mentioned unlimited as to its operative position; to simplify the construction so that the operative parts may be quickly and readily removed for repair or replacement; and to provide automatic devices for closing the passage to the overflow and the spill-way, said devices being assembled for handling as a unit when being installed.

One embodiment of the present invention is shown in the accompanying drawings, in which—

Figure 1 is a longitudinal section of an injector constructed and arranged in accordance with the present invention, the section being taken on the median plane of said injector; Fig. 2 is a detail view in perspective, showing the combining tube and support therefor; Fig. 3 is a detail view in perspective of the main ring valve employed in the present invention; Fig. 4 is a detail view in perspective, of the delivery tube employed by me; Fig. 5 is a detail view in perspective, of an auxiliary ring valve.

To install in position the injector herein-after described, the pipe unions 10 and 11 are connected with the steam delivery pipe of the boiler controlled by a throttle valve of suitable character, and to the water-delivery pipe of the boiler. The injector body 12 is interposed between two unions, and is connected to each by collar nuts 13. The body 12 is similarly connected to the union 14 with which the water-supply pipe is connected, and this by means of a third collar nut 15.

The body 12 is longitudinally bored to form a main passage therethrough, providing a normally straight-line communication between the steam pipe and union 10 and the water feed pipe and union 11. Lateral bores disposed at right-angles to the main bore form the water intake chamber 16 and the overflow chamber 17. Intermediate the

water intake chamber 16 and the overflow chamber 17, the wall of the body is preferably thickened to form a tapped section 18, into which is screwed as a plug, a lifting tube 19.

By threading the lifting tube 19 and the thickened portion of the injector body, there is provided an opportunity to adjust the lifting tube 19 with relation to a steam tube 20 and a nozzle extension 21. In this manner, the air gap between the delivery end of the nozzle 21 and the intake end of the lifting tube 19 is increased or diminished. The steam tube 20 is provided with an annular flange 22, an annular pocket or seat for which is formed in the end of the body 12, to be drawn against the union 10 by the collar nut 13, to form a solid and tight joint. It will be seen that the construction described provides for the ready and rapid installation of the tube 20 in the body 12.

With equal facility, a combining tube 23 and a delivery tube 24 are installed. The installation of the last-named tubes may be separately or jointly, as desired, the delivery tube 24 being nested within a cage 25. The cage 25 snugly fits the bore of the body 12, and is provided at the end adjacent the boiler with an annular flange 26, which rests on a shoulder provided on the end of the body 12, as a seat for said flange to regulate the extension of the tube 23 within said body. The outer end of the flange performs a like office for the flange 27 on the delivery tube 24. Both flanges are clamped tightly between the body 12 and the union 11 by the collar nut 13.

The cage 25 is bored to provide a chamber allowing ample space between the inner wall thereof and the outer wall of the tube 24. The chamber in said cage 25 is normally in open communication with the boiler pipe or union 11 thereof through orifices 28 formed in the flange 27. A similar function is performed by spill-holes 29, which are bored through the base of the tube 23 and normally form communicating passages between the overflow chamber 17 and the chamber within the cage 25.

Under normal conditions, the longitudinal bore or passage formed thereby in the body 12 is in open communication with the overflow chamber 17. Likewise, the interior of the cage 25 is in open communication with said chamber. It is to cut out the overflow

chamber, during the delivery of water to the boiler, that I provide the main ring valve 30 and an auxiliary ring valve 31.

To receive the ring valve 30, the upper reduced section of the tube 23 is provided with a cylindrical shape to form a guide for said ring valve. The valve 30 fits said reduced section, and is machined to provide a flat surface 32. A valve seat is 13 ground on the lower edge of the flange 33, which flange is extended partly across the overflow chamber 17 to form a vacuum chamber 34, and at the lower end thereof to permit the grinding of a seat for the 15 valve 30. When not in service position for closing communication between the chambers 17 and 34, the valve 30 rests on a shoulder 35.

The upper edge of the ring valve 31 is 20 ground to form an inclined valve surface 36, while the upper end of the chamber formed in the cage 25 is correspondingly ground to form a seat for the valve. When, 25 in service position, the valve 31 is lifted to its seat, the spill-holes 29 are closed, and communication between the chamber inside 30 of the cage 25 and the overflow chamber 17 is cut off. Thus, when the valves 30 and 31 are both in service position, or raised to their respective seats, the overflow chamber 17 is completely cut off, and so remains during the delivery of water from the water-supply pipe to the boiler feed pipe.

With an apparatus constructed and arranged as described, the operation is as follows:—When the steam is permitted to flow, it passes under pressure through the tube 20 and the nozzle extension 21 thereof to the lifting tube 19. The interior of the 40 nozzle 21 is contracted or throated adjacent the tube 20, and expanded outward to the delivery end adjacent the tube 19. The steam, being permitted to expand, clears the nozzle with slightly increased speed and the 45 air gap between the end of said nozzle and the tube 19. The air gap between the ends of said tube and said nozzle is within the water intake chamber 16. If said chamber is filled with air, this is drawn by the onrush of the steam into the lifting tube 19 until a rarefaction of air is produced in 50 said chamber sufficient to lift the water in the water-supply pipe to flood said chamber 16. Before the water enters the chamber 16, steam and the air which are in the chamber 16 and pipe connected therewith are carried into the chamber 34, spreading 55 therein around the tube 23, to pass therefrom through the overflow chamber 17 to the open air. This action continues until 60 the air has been exhausted from the chamber 16 and replaced by water. Thereafter the steam drives the water, instead of the air, through the lifting tube 19. The delivery end of the tube 19 is slightly con-

tracted to deliver the water as a jet within the flared end of the combining tube 23. The combining tube 23 conveys the water and steam as a solid column and delivers the same to the delivery tube 24, from whence said water and steam enters the boiler feed pipe by way of the union 11.

During the inoperative period of the injector, it will be understood, a certain proportion of air is held in the boiler feed pipe. This air is drawn outward from the boiler feed pipe and union 11 through the orifice 28 in the flange 27, and from the chamber within the cage 25. The air from the feed pipe and from the chamber in the cage 25 is drawn outward by the suction of the air therefrom due to the passage of the column of water across the gap 37. The width of the gap 37 is regulated to suit operative conditions, the means for regulating the same being the screw-threads which are formed on the flanges 26 and 27 of the cage 25 and tube 24. The air thus drawn or expelled through the boiler feed pipe is delivered through the spill-holes 29. When the air has been thus removed from the feed-pipe and the admission thereof to the boiler has been thereby avoided, the water flows into the chamber of the cage 25, seeking exhaust by way of the spill-holes 29. The delivery of the water is avoided by the operation of the ring valve 31. The valve 31 is lifted from the shoulder 38 on which it normally rests, as shown by the dotted lines in Fig. 1, by the outward rush, in the first instance, of the air and the water following the same.

In the manner above described, it will be observed, the delivery of steam or water from the overflow opening 17 is completely avoided during the delivery of water from the water-supply pipe to the boiler feed pipe. If there is a "break" in the operation of the injector, the ring valves 30 and 31 do not operate, and the steam delivered to the body of the injector has free access to the overflow chamber 17 and thence to the open air, advising in this manner the engineer of the failure of the injector to operate.

The perfect operation of the injector is dependent in a large measure upon the gaps between the delivery end of the nozzle extension 21 and the receiving end of the tube 19, and between the delivery end of the combining tube 23 and the receiving end of the delivery tube 24. As the conditions are not permanent, the means herein provided; to wit, the screw-threaded constructions whereby the tubes 19, 23 and 24 are held, allow for the proper adjustment of said tubes.

Claims:

1. An injector, comprising a body portion bored to form a longitudinal passage, a vacuum chamber therein and an open-ended

overflow chamber disposed perpendicular to and opening from said longitudinal passage; a combining tube permanently mounted in said longitudinal passage, extending across said overflow chamber and into said vacuum chamber, said tube having spill-holes formed therein and approximately parallel to the passage in said tube for the delivery of air from the boiler feed pipe to which the injector is attached; a delivery tube coaxially disposed with said combining tube and spaced apart therefrom to provide a suction gap to draw the air from said boiler feed pipe; means for adjusting the relation between said tubes to vary the suction gap; and a ring valve guidedly mounted on said delivery tube and operable by the suction of said gap to close said spill-holes.

2. An injector, comprising a body portion bored to form a longitudinal passage, a vacuum chamber therein and an open-ended overflow chamber disposed perpendicular to and opening from said longitudinal passage; a combining tube mounted in said longitudinal passage and extending across said overflow chamber and into said vacuum chamber, said tube having spill-holes formed therein and approximately parallel to the passage in said tube, for the delivery of air from the boiler feed pipe to which the injector is attached; a delivery tube co-axially disposed with said combining tube and spaced apart therefrom to provide a suction gap to draw the air from said boiler feed pipe; means for adjusting the relation between said tubes to vary the suction gap; a relatively light ring valve mounted on said combining tube and operable by the suction in said vacuum chamber to close said vacuum chamber; and a ring valve guidedly mounted on said delivery tube and operable by the suction of said gap to close said spill-holes.

3. An injector, comprising a body portion bored to form a longitudinal passage, a vacuum chamber therein, and an open-ended overflow chamber disposed perpendicular to and opening from said longitudinal passage; a combining tube mounted in said longitudinal passage and extending across said overflow chamber and into said vacuum chamber, said tube having spill-holes formed therein and approximately parallel to the passage in said tube, for the delivery of air from the boiler feed pipe to which the injector is attached; a delivery tube co-axially disposed with said combining tube and spaced apart therefrom to provide a suction gap to draw the air from said boiler feed pipe; means for adjusting the relation between said tubes to vary the suction gap; a relatively light ring valve mounted on said combining tube and operable by the suction in said vacuum chamber to close said vacuum chamber; a ring valve guidedly mounted on said delivery tube and operable by the suction of

said gap to close said spill-holes; a water-supply; and a nozzle co-axial with the combining tube and vacuum chamber, for the delivery of steam and water to said combining tube through said vacuum chamber. 76

4. An injector, comprising a body portion bored to form a longitudinal passage, a vacuum chamber therein and an open-ended overflow chamber disposed perpendicular to and opening from said longitudinal passage a combining tube permanently mounted in said longitudinal passage, extending across said overflow chamber and into said vacuum chamber, said tube having spill-holes formed therein and approximately parallel to the 80 passage in said tube, for the delivery of air from the boiler feed pipe to which the injector is attached; a delivery tube coaxially disposed with said combining tube and spaced apart therefrom to provide a suction gap to draw the air from said boiler feed pipe; and a ring valve guidedly mounted on said delivery tube and operable by the suction of said gap to close said spill-holes. 85 90

5. An injector, comprising a body portion bored to form a longitudinal passage, a vacuum chamber therein and an open-ended overflow chamber disposed perpendicular to and opening from said longitudinal passage; 95 a combining tube mounted in said longitudinal passage and extending across said overflow chamber and into said vacuum chamber, said tube having spill-holes formed therein and approximately parallel to the 100 passage in said tube, for the delivery of air from the boiler feed pipe to which the injector is attached; a delivery tube coaxially disposed with said combining tube and spaced apart therefrom to provide a suction gap to draw the air from said boiler feed pipe; a relatively light ring valve mounted on said combining tube and operable by the suction in said vacuum chamber to close said vacuum chamber; and a ring valve guidedly mounted on said delivery tube and operable by the suction of said gap to close said spill-holes. 110

6. An injector, comprising a body portion bored to form a longitudinal passage, a vacuum chamber therein, and an open-ended overflow chamber disposed perpendicular to and opening from said longitudinal passage; a combining tube mounted in said longitudinal passage and extending across said overflow chamber and into said vacuum chamber, said tube having spill-holes formed therein and approximately parallel to the passage in said tube, for the delivery of air from the boiler feed pipe to which the injector is attached; a delivery tube coaxially disposed with said combining tube and spaced apart therefrom to provide a suction gap to draw the air from said boiler feed pipe; a relatively light ring valve mounted 120 125 130

on said combining tube and operable by the suction in said vacuum chamber to close said vacuum chamber; a ring valve guidedly mounted on said delivery tube and operable by the suction of said gap to close said spill-holes; a water-supply; and a nozzle coaxial with the combining tube and vacuum chamber, for the delivery of steam and water to said combining tube through said vacuum chamber.

Copies of this patent may be obtained for five cents each, by addressing the "Commissioner of Patents, Washington, D. C."

In testimony whereof I have signed my name to this specification in the presence of two subscribing witnesses.

HOMER EMERSON HASKELL.
